TEMPERATURE-CONTROL DEVICE.

Application filed December 8, 1926. Serial No. 153,266.

My invention relates to control devices, and particularly to thermally and mechanically actuated instruments.

An object of my invention is to provide a 5 temperature control instrument that shall have a plurality of contact members controlled selectively and intermittently by means of a thermal responsive device and a periodically-controlled clamping member. 10 Another object of my invention is to provide a temperature-control instrument that shall have means responsive directly to the temperature of a body to be controlled for selectively engaging one of a plurality of 15 contact members and that shall have a periodically controlled clamping member for effecting selective engagement of the contact member with a stationary contact.

In practicing my invention I provide a 20 thermo-responsive means in the form of a metallic spiral that is adapted to be subjected to the temperature of a body to be controlled. A pivotally mounted pointer is adjustably secured to the thermo-responsive means and 25 is adapted to be periodically clamped into engagement with one of a plurality of contact members by means of a magnet coil and an armature controlled thereby.

In the drawings,

30 Fig. 1 is a top plan view in elevation, partially in section, of a device embodying my invention;

Fig. 2 is a side view in elevation, partially in section, of the device illustrated in Fig. 1;

35 Fig. 3 is a view thereof, in vertical section, taken on the line III—III of Fig. 2; and

Fig. 4 is a diagrammatic view of the 40 device illustrated in Figs. 1 and 2, as applied to the control of an electrically heated device.

45 In the drawings, a temperature control device 11 comprises a magnetically controlled clamping mechanism 12, a plurality of movable contacts 13 and 14 controlled thereby, a movable pointer 15 and a thermal-responsive means 16 for actuating the pointer 15.

The magnetically-controlled clamping mechanism comprises a base 17, a magnet coil 18 mounted thereon, and an external magnetic path 19 therefor. One terminal 20 of 50 the magnet coil is secured to the base 17.

The external magnetic path 19 comprises a stationary member 21 and an armature 22 supported thereby. The stationary member 21 comprises a portion 23 that extends up-

wardly at an edge 24 of the base 17. The 55 portion 23 is provided with a projection or pin portion 25 located at the end thereof and a bolt 26 which extends laterally therefrom. A portion 27 of the member 21 extends along the bottom edge of the base 17, and a portion 60 28 thereof extends substantially at right angles thereto and projects through an aperture 29 in the base 17.

The coil 18 and the stationary member 21 are secured to the base 17 by means of a bolt 65 31 that extends through the coil 18, the base 17 and the portion 27 of the member 21.

The armature 22 is of substantially U-shape and comprises a pair of depending portions 32, 33 and a connecting portion 34. 70 The portion 34 is provided with a circular aperture 35 and the portion 32 is provided with an elongated aperture 36. An angle piece 37 is secured to the portion 33 by any suitable means such as a machine screw. The 75 portions 33 and 28 are substantially in engagement when the magnet coil 18 is energized.

The aperture 36 in the portion 32 of the armature 34 so registers with the bolt 26 that 80 the projection 25 extends through the circular aperture 35. A coil spring 38 extends coaxially along the bolt 36 and is forced against the portion 32 with a suitable pressure by means of nuts 39.

85 A member 41, of substantially U-shape, extends across the base 17 along the edge 24 and is suitably secured thereto. The member 41 is provided with a pair of upwardly extending end portions 42 and 43. The portion 42 has a portion 44 bent over at substantially right angles thereto and supports a resilient angle piece 45 that is suitably secured thereto.

90 A clamping member 46 is pivotally supported by the portions 42 and 43 of the member 41 and comprises a portion 47 and a pair of end portions 48 and 49 extending substantially at right angles thereto. The portion 49 has its end so bent that it registers with an aperture in the portion 43 of the member 41. The portion 48 is provided with an end portion 51 of substantially U-shape which protrudes through an aperture 52 in the portion 42 and registers with the angle piece 45. The angle piece 45 serves to bias the member 46 towards the position substantially as illustrated in Figs. 2 and 3 of the drawings.

100 When the coil 18 is energized, the member

46 is clamped into engagement with the pointer 15 by means of the armature 34 and the angle piece 37 secured thereto.

The contacts 13 and 14 are suitably secured to a pair of resilient spring members 53 and 54, of substantially U-shape, that are secured to the bottom surface 45 of the base 17 by any suitable means, such as machine screws. A cooperating stationary contact 55 for the contacts 13 and 14, is suitably secured to the base 17. A spacing member 56 is secured to the base 17 and serves to prevent the pointer 15 from engaging the contacts 13 and 14 simultaneously.

15 A pair of angle pieces 57 (see Fig. 3) are secured to the base 17 at the underside thereof by suitable bolts 58 and extend upwardly therefrom. End portions 59 of the members 57 are provided with bolts 60.

20 A cover member 61 serves to enclose the magnetically controlled clamping mechanism 12 and is supported by and secured to the members 57 by a pair of nuts 62, only one of which is shown, (see Fig. 2), that have screw-threaded engagement with the bolts 60.

25 The base 17 is suitably secured to a longitudinally extending member 63 by such means as machine screws or rivets.

30 The pointer 15 is secured to a pivotally mounted member 64 by rivets 65 that extend through the member 64 and register with a return bent portion 66 of the pointer 15. A pivot 67 is secured to substantially the central portion of the member 64 and is supported 35 between bearings 68 and 69. The bearing 68 is secured to the member 63 and the bearing 69 is secured to a member 70 of substantially U-shape, which in turn, is secured to the member 63 by such means as rivets 71. A portion 40 72 of the bearing 68 projects through the member 63 for a purpose to be hereinafter explained. A resilient spring 74 is secured to an end 75 of the member 64 and forms substantially a Y therewith.

45 A clamping member 76 is provided for securing the temperature control device 11 to a body whose temperature is to be controlled and comprises a pair of portions 77 and 78 that extend laterally from the member 63, and a pair of flange portions 79 and 80 that extend laterally from the portions 77 and 78.

50 A portion 81 of the member 76 is bent substantially at right angles to the member 63 and is provided with a tail piece 82 that is bent 55 at an angle to the portion 81. A bolt 83 extends through the portion 82 and serves to clamp the device 11 into engagement with the body whose temperature is to be controlled.

55 The thermal-responsive means 16 comprises a metallic spiral 84, one end of which is secured to a rod 85 and the other end to a member 86 of substantially L-shape. If so desired the spiral 84 may be made of suitable bimetallic material. The rod 85 extends upwardly 60 through the aperture 87 in a portion 88 of the

member 86 and has a disc 89 secured to the end thereof. A plurality of pins 90 are disposed along the periphery of the disc 89 and are adapted to fit between the spring 74 and the portion 75 of the member 64. The pins 90 70 may be utilized for determining the initial angular position of the pointer 15 with respect to the member 63, which position determines the temperature setting of the relay.

The member 86 is secured to the member 76 75 by means of a rivet.

The member 63 is secured to the clamping member 76 by means of screws 91. The screws 91 extend through arcuate apertures located in the member 63 and have screw-threaded 80 engagement with the member 76 (see Figs. 1 and 2).

The portion 72 of the bearing 68 projects through the members 63 and 76, thus providing a pivot about which the member 63 may be turned. By loosening the screws 91, the member 63 may be positioned at any desired angle, either to the right or the left, relatively to the position illustrated in Fig. 1, in which position it may be clamped firmly by the 90 screws 91.

95 By reason of the fact that the member 63 and the pointer 15 may be positioned in any desired angular position, either to the right or the left of their positions as illustrated in Fig. 1, the initial temperature setting or adjustment of the relay 11 may be so controlled that it can be adapted to operate over a wide range of temperatures.

100 When the metallic spiral 84 is subjected to the temperature of a body to be controlled, it expands upon increasing temperature to turn the disc 89, thereby imparting motion to the pointer 15.

105 In Fig. 4 of the drawing, I have illustrated the temperature control device 11 as a means for controlling the temperature of a body 92. The magnet coil 18 is intermittently energized by a rotating commutator 93, which may be driven by a motor 94, suitable for the 110 purpose. When the segments 95 of the commutator 93 make contact with the brushes 96, the coil 18 is energized from a source of electromotive force 97 to actuate the armature 34a downwardly thereby clamping the pointer 15 115 into engagement with one or the other of the contact members 13 and 14.

120 When the pointer 15 is in the position illustrated in Fig. 4 of the drawings, the armature 34a, when attracted by the coil 18, clamps the contact member 14 into engagement with the stationary contact member 55, causing a coil 99 to be energized from a source of electromotive force 100. The coil 99, when energized, actuate a switch mechanism 101 which, in turn, causes a resistor 102 to be energized from a source of electromotive force 103 for heating the body 92.

125 When the temperature of the body 92 has increased to a predetermined value, the point- 130

er 15 will have been actuated to such a position that the contact member 13 engages the contact 55. A magnet coil 104 is then energized which, in turn, so actuates the switch mechanism 101 that the resistor 102 is de-energized. If the temperature falls below a predetermined value, the pointer 15 is actuated substantially to the position illustrated in Fig. 4 of the drawings. If, when in this position, the contact member 14 is moved into engagement with the contact member 55 by means of the coil 18 and the armature 34a, the coil 99 is energized to actuate the switch 101, which, in turn, energizes the resistor 102.

By my invention, I have provided a sensitive temperature-control device that is simple in construction and rugged. The device comprises a movable pointer that is actuated by a metallic spiral which may be directly subjected to relatively high temperatures, and an intermittently controlled clamping mechanism for clamping the pointer into engagement with one of a plurality of contact members.

Various modifications may be made in the device embodying my invention without departing from the spirit and scope thereof. I desire, therefore, that only such limitations shall be placed thereon as are imposed by the prior art and the appended claims.

I claim as my invention:

1. In a temperature control instrument, the combination with a thermo-responsive metallic member of spiral-shape, a stationary contact member, a plurality of movable contact members, and a pivotally mounted member for selectively actuating one of said plurality of contact members into engagement with said stationary contact member, of means controlled by said thermo-responsive member for actuating and for controlling the initial position of said pivotally mounted member, said means comprising a disc member and a plurality of spaced pin members disposed along the periphery thereof for registering with one end of said pivotally mounted member.

2. A temperature control instrument comprising a metallic member of spiral-shape, a support therefor, a rotatable member opera-

tively secured to one end of said metallic member, a disc member operatively associated with the rotatable member, said disc member having a plurality of pin members disposed along its periphery, a pivotally mounted member having one end thereof in selective engagement with said pin members, a movable contact member, and an electromagnetically controlled member for periodically clamping the pivotally mounted member into engagement with said movable contact member.

3. A thermal relay comprising a thermo-responsive metallic spiral, a disc member having a plurality of pin members disposed along the periphery thereof, said disc member being controlled by the spiral in accordance with the temperature thereof, a pivotally mounted member for controlling a movable contact member, said pivotally mounted member having one end thereof in engagement with one of said pin members, a contact member, and magnetically controlled means for periodically clamping the pivotally mounted member into engagement with said contact member.

4. A temperature control device comprising a plurality of movable contact members and a cooperating stationary contact member, means for selectively controlling said movable contact members in accordance with a thermal condition to be controlled, a metallic spiral member adapted to be subjected to the thermal condition for actuating said means, and means associated with the spiral for biasing the first-named means to a predetermined initial position.

5. In a temperature-control device, in combination, a support, a thermo-responsive member mounted thereon, a contact-supporting member carried by said support, a pointer pivotally mounted on said contact-supporting member for actuating the contact members, and means for varying the angular relation of the support to the contact-supporting member.

In testimony whereof, I have hereunto subscribed my name this 6th day of December, 1926.

EARL K. CLARK.
